CLAIM

The ornamental design for a case for a hair roller set, as
shown and described.

DESCRIPTION

FIG. 1 is a front elevational view of a case for a hair
roller set showing my new design;

FIG. 2 is a top plan view thereof;

FIG. 3 is a rear elevational view thereof;

FIG. 4 is a bottom plan view thereof;

FIG. 5 is a left side elevational view thereof;

FIG. 6 is a front and right side perspective view thereof
with the case cover pivoted to open position.
